[57] CLAIM

The ornamental design for a lawn sprinkler, as shown and described.

DESCRIPTION

FIG. 1 is a perspective view of a lawn sprinkler in accordance with the present invention.

FIG. 2 is a front elevational view of the lawn sprinkler of FIG. 1.

FIG. 3 is a top plan view of the lawn sprinkler of FIG. 1.

FIG. 4 is a side elevational view of the lawn sprinkler of FIG. 1.

FIG. 5 is a perspective view of the lawn sprinkler shown in an alternate use; and,

FIG. 6 is a front elevational view of the lawn sprinkler of FIG. 5.

The broken lines shown in the drawings are for illustrative purposes only and for no part of the claimed design.
